UNITED STATES PATENT OFFICE

LANCELOT MARTIN SIMPSON, OF LEEDS, ENGLAND, ASSIGNOR TO ASSOCIATED TELEPHONE AND TELEGRAPH COMPANY, OF KANSAS CITY, MISSOURI, A CORPORATION OF DELAWARE

TELEPHONE SYSTEM

Application filed April 25, 1928, Serial No. 272,609, and in Great Britain May 11, 1927.

The present invention relates to telephone systems and is more particularly concerned with apparatus for performing so-called routine tests. It is generally realized that with complicated apparatus of the type used in automatic telephony it is desirable that each piece of apparatus should be tested periodically to make sure that it is fulfilling all its functions, since by this means faults may be brought to light and corrected before they occur in the actual setting up of connections by subscribers. The present invention is particularly applicable to the testing of register senders of the kind adapted to respond to impulses of one type sent in and thereafter to transmit impulses of another type, but certain of its features are capable of more general application.

In order that the routining shall be properly effective it is important to make sure that each piece of apparatus shall be tested, and since in the general way the apparatus will be available for use by subscribers at the time the routine test is made it may be necessary for the routiner to wait in association with a particular piece of apparatus until it becomes free. According to one feature of the present invention, if a piece of apparatus is found busy when it is seized by the routiner, this waits for a definite time interval and if the apparatus has not been returned to common use at the end of this period, an alarm is given and the particular apparatus indicated, and at the same time the routiner seizes the next piece of apparatus so that the test can continue without wasting an undue amount of time in case the attendant is not able to look into the fault immediately.

It is also very usual in routining apparatus of the kind considered to make special arrangements for routining a particular piece of apparatus a number of times as might be desirable for instance in case it had originally developed a fault which had subsequently been rectified by the attendant. In previous arrangements of this type after the operation of the special key for effecting continuous routining, it has been usual for the attendant to operate special stepping keys to step the distributing switches into

engagement with the particular piece of apparatus under consideration. According to another feature of the invention, however, the necessity for this operation is obviated in that a special jack field is provided and when the attendant wishes to perform a continuous routine of any piece of apparatus he inserts a plug in the jack associated therewith and then operates the continuous routine key whereupon the distributing switches hunt automatically to find the piece of apparatus in question.

The invention will be better understood from the following description of one method of carrying it into effect which is given by way of example. This arrangement is intended to test the so-called "coders" used in the call indicator arrangement described in the patent of W. O. Passmore, No. 1,716,563 issued June 11, 1929. Reference to this specification will show that a coder is associated with the outgoing end of a junction extending to a manual exchange when the associated repeater is taken into use and that the digits subsequently dialled by a subscriber are registered in turn in the coder. When the operator at the manual exchange is ready to receive the call, a certain switching operation is performed at the incoming end of the junction and thereupon the coder commences to send code impulses corresponding to the digits received. A routiner for testing such coders must therefore incorporate an arrangement in which impulses are sent to the coder and the special code impulses sent out therefrom are received on appropriate storage relay groups.

Referring now to the accompanying drawings comprising Figs. 1 to 10 inclusive, Figs. 1 to 6 and Fig. 8 show various relays controlling the operation of the routining equipment; Fig. 7 shows the counting switch CGS and also the control switch CS which determines the digits which are impelled into the coder; Fig. 9 shows the primary distributor PD to the banks of which a suitable number of secondary distributors SD are connected, and also shows the busy marking switch BS for indicating a particular coder which has been found busy for an excessive length of 100

time; while Fig. 10 shows the sending switch SES, the test switch TES, and the pause timing switch PTS which ensures the correct pause between the sending of digits.

- 5 Access to the various coders from the routining equipment is obtained by means of the primary and secondary distributors, the secondary distributors being advanced one step when a coder has been completely tested so as 10 to connect up the next coder, and the primary distributor being also advanced one step when all the coders accessible from one secondary distributor have been dealt with.

When it is desired to carry out a test the 15 attendant will operate the start key 10, Fig. 6, thereby energizing slow-to-pull-up relay ST and also closing a circuit over the back contact 11 of relay ST, springs of continuous routine key 12, conductor 13, driving magnet 20 DM1 of the primary distributor PD to battery. When relay ST is fully operated, this circuit is opened and the magnet de-energizes moving the wipers of the primary distributor PD into contact with the first secondary distributor SD. At armature 14 relay ST closes a circuit from earth on resting contact of armature 15, conductor 16, working contact of armature 14, slow-to-pull-up relay CRR to battery, and also over the resting contact of 25 armature 17, conductor 18, wiper 19 and first bank contact of the primary distributor PD, driving magnet DM2 of the secondary distributor SD to battery. This circuit is maintained during the slow operating time of relay CRR and when relay CRR is fully operated is broken so that the driving magnet DM2 releases and moves the wipers of the secondary distributor forward one step so that they are now in engagement with the 30 first coder.

It will be understood that conductors from the coders are connected to the banks of the secondary distributors and it will be assumed that the release trunk conductor is 45 wired to bank 32, the pulse conductor to bank 105 and the negative and positive lines to banks 131 and 144 respectively. At armature 20 relay ST operates relay STR; at armature 21 prepares the operating circuit for 50 relay A when the first coder is available for testing; and at armatures 22, 23 and 31 opens the homing circuits of the test switch, the primary distributor and the sending switch respectively.

55 Relay STR upon operating at armature 25 earths the motor start conductor 26, while at armature 27 a point in the homing circuit of the secondary distributor SD is opened. It should be understood that there 60 will be sufficient contacts such as 27 and 28, 29 and 30 on relays STR and CR to provide homing circuits for all the secondary distributors which may be equipped.

As the coders will be available for com- 65 mon use during the time that routining op-

erations are carried out, it will be appreciated that the particular coder on which the secondary distributor wipers are now standing may be in use on a regular call. The routining equipment will therefore wait for a time interval and commence its testing as soon as the coder again becomes free. As the holding time of a coder in the setting up of a regular call is comparatively short, the testing will be commenced after only a brief wait, but if the holding time becomes excessive, as for instance, if the coder has been artificially busied, the routiner will step to the next coder and commence testing thereon. The busy marking switch BS will then rotate 70 to contacts associated with the coder found busy and cause the associated lamp to flash and an alarm to be brought into action thereby calling the attention of the attendant. In the meantime, testing will proceed on the 75 other coders, but if a second busy coder is encountered the testing will be stopped and an urgent alarm signal operated.

Assuming first that the first coder is busy, the guarding earth from the release trunk 80 conductor of the coder will be extended over bank contact and wiper 32 of the secondary distributor, bank contact and wiper 33 of the primary distributor, conductor 34, springs of key 35, conductor 36, working contact of armature 21, conductor 37, resting contact of armature 56, winding of relay A to battery. Relay A operates and at armature 39 opens a point in the energizing circuit of relay B, while at armatures 40 and 41 circuits 85 are prepared for relay TP by means of which the alarm will be brought into operation after a time interval. The action of the busy marking switch to indicate this coder if it is held busy for more than a predetermined 90 time will be described later, as also will the 95 operation of the alarm circuits, and it will now be assumed that the coder is returned to common use almost immediately. Relay 100 A will thereupon release as the guarding earth is removed and relay B will operate over a circuit which may be traced from earth, working contact of armature 410 of relay ST, conductor 42, wiper 43 and first bank contact of the test switch TES, conductor 44, resting contacts of armatures 39 and 45, winding of relay B to battery. Relay B operates, thereupon at armature 46 105 closing a locking circuit for itself over resting contact of armature 47, conductor 48, working contact of armature 20 to earth, and at armature 49 completing a circuit to operate relay SDD, from the earth on wiper 50 of the test switch TES and its first bank contact, normal contacts of cancel test No. 1, key 51, conductor 52, working contact of armature 49, conductor 53, winding of relay SDD to battery. The operation of relay B 110 also extends earth by way of both windings of relay PS, Fig. 3, in series, resting con- 115

tact of armature 54, conductor 55, working contact of armature 56 of relay B, conductor 37, working contact of armature 21, conductor 36, key 35, conductor 34, wiper 33 and bank contact of the primary distributor, wiper 32 and bank contact of the secondary distributor to the release trunk conductor of the coder, and thence to battery through a relay in the coder circuit. Relay PS now operates, thus short-circuiting its upper high resistance winding at armature 57 and thereby maintaining a low resistance earth on the guarding conductor of the coder to mark it busy, and the relay connected to the release trunk in the coder operates and prepares various holding and operating circuits for the coder storing, switching and controlling relays. Relay B also causes the operation of relay SS at armature 58 from earth, wiper 59 and bank contact of the control switch CS, Fig. 7, conductor 60, working contact of armature 58, resting contact of armature 61, winding of relay SS to battery, and also at armatures 62, 63 and 64 extends various testing leads to the wipers of the primary distributor. At armature 65 earth is extended from resting contact of armature 66 over conductor 67 to wiper 68 of the test switch and thence to an indicating lamp to indicate which test is in progress, so that as the test switch advances to initiate the different tests the corresponding lamps will be lit from successive bank contacts. It will also be noticed that earth is extended from resting contact of armature 69 of relay CR, Fig. 6, conductor 70, wiper 71 and bank contact of the primary distributor PD, wiper 72 and bank contact of the secondary distributor SD to an indicating lamp, so that a visual indication is afforded of the particular coder under test.

The operation of relays SS and SDD prepares a circuit extending from earth, working contact of armature 73, conductor 74, working contact of armature 75, conductor 76, resting contacts of armatures 77 and 78, lamp 405, upper low resistance winding of relay PSS to battery. It will be remembered, however, that relay PS has just operated from the release trunk of the coder, thereby opening a point in the above circuit at armature 77 so that relay PSS will not operate. Assuming, however, that due to some fault in the release trunk circuit of the coder, relay PS does not operate, the circuit for relay PSS will be complete and the operation of relay PSS will energize relay FA at armature 80, and the latter relay will then bring in an alarm as will be described later.

The operation of relay SS also extends earth from the working contact of armature 130, conductor 131, first bank contact and wiper 132 of the control switch CS, interrupter springs, driving magnet DM4 to battery, thus causing the control switch to step to its second contacts. This earth from armature 130 is also extended over conductor 133, resting contact of armature 91, conductor 92, to relay RA which therefore operates. Further, earth impulses from the impulse springs 81, which are conveniently operated 10 times per second, are connected over resting contact of armature 82, working contact of armature 83, conductor 84, resting contact of armature 85, lower winding of two-step relay PA to battery. Relay PA initially operates partially in the well-known manner and operates fully when the impulse springs open, thereupon at armature 85 switching the earth impulses to the driving magnet DM3 of the sending switch SES, Fig. 10, over conductor 86, resting contact of armature 87 and conductor 88. The locking circuit for relay PA is from earth, resting contact of armature 117, working contact of armature 118, conductor 119, resting contact of armature 116, conductor 134, working contact of armature 135, both windings of relay PA in series to battery. The wipers of the sending switch will therefore be stepped round the bank, and as they step to the second set of contacts, earth extended from second bank contact and wiper 89 over conductor 90 operates relay SA. At armature 93 relay SA lights the lamp 128 to indicate that the routine equipment is in the process of sending a number into the coder; at armature 91 opens the initial operating circuit of relay RA and at the working contact of the same armature connects earth pulses also at the rate of 10 per second from impulse springs 413 to the relay RA over conductor 92 and accordingly relay RA will now impulse. On its first operation it extends earth from working contact of armature 93 of relay SA, conductor 94, working contact of armature 95 to relay RB which operates and being slow to release remains in operated condition during the impulsion of relay RA. The operation of relay RB completes a circuit to the pulse conductor to the coder, which may be traced from earth, working contact of armature 93, conductor 94, resting contact of armature 95 during those periods that relay RA is normal, conductor 96, resting contact of armature 97, conductor 98, working contact of armature 99, conductor 100, resting contact of armature 101, conductor 102, working contact of armature 63, conductor 103, wiper 104 and bank contact of the primary distributor, wiper 105 and bank contact of the secondary distributor to the pulse lead to the coder under test. As relay RA impinges therefore, earth will be connected a number of times to the pulse conductor of the coder. The sending switch is stepping round its bank during this time and as it reaches its sixth contact earth is extended from wiper 106 of the control switch, first bank contact, conductor 107, resting contact of armature 108, con-

ductor 109, sixth bank contact and wiper 110 of the sender switch SES, conductor 111, winding of relay SZ to battery. Since springs 81 and 413 open and close in synchronism it will be seen that by the operation of relay RA four impulses have been transmitted to the coder and now the operation of relay SZ opens the circuit to the pulse conductor at armature 97. At armature 112 earth is extended to maintain relay RA in the operated position to prevent an additional impulse being sent; at armature 113 a locking circuit is closed for relay SZ over conductor 114, contacts of the pause timing switch bank and wiper 130 to earth over conductor 42 and armature 410 of relay ST; at armature 87 the stepping pulses are disconnected from the magnet DM3 of the sender switch; at armature 115 the circuit to return the sender switch to its home position is closed from earth, wiper 89 and bank contacts, conductor 90, working contact of armature 115, conductor 414, interrupter springs, magnet DM3 to battery, at armature 116 a point in the locking circuit of relay PA is opened and relay PA releases; at armature 120 earth is extended over conductor 121 to the magnet DM4 of the control switch, so that the magnet is held energized, and at armature 122 earth pulses, at conveniently the rate of 20 per second, are extended from conductor 123 to two-step relay QX which operates in known manner, locking itself at armature 124 to earth at armature 112 and extending the earth pulses at the working contact of armature 125 to conductor 126 and thence to the driving magnet DM8 of the pause timing switch.

In consequence of the completion of the circuit traced above, the sender switch is returned to its normal position and thereupon relay SA releases as its circuit is opened. Relay RA, however, remains energized over the back contact of armature 91 to earth at the front contact of armature 130 over lead 133, but relay RB releases as its circuit is opened when SA restores. The pause timing switch magnet will now step the wipers round the bank, under the influence of the earth impulses at 20 per second, and when it has made a predetermined number of steps, in the case of the connections shown in the drawing six steps, the holding circuit of relay SZ is opened and relay SZ releases, disconnecting the stepping pulses from the driving magnet DM8 and allowing relay QX to release. Moreover the control switch magnet DM4 will now de-energize and advance the wipers to the third set of contacts and, further, at the back contact of armature 87 the locking circuit of two-step relay PA will be closed so that relay PA will lock up and again connect impulse springs 81 to the magnet of the sender switch. The wipers of the sender switch will accordingly be stepped round the bank again and relays SA, RA and RB will operate as before so that impulses will be sent to the coder over the pulse conductor. When four such pulses have been sent, the wipers of the sender switch will encounter earth from the control switch wiper 106, third bank contact, conductor 125, resting contact of armature 126, conductor 109, and thence as previously traced, causing the operation of relay SZ and consequently causing the homing of the sending switch, operation of the pause timing switch, and stepping of the control switch as has just been described. These operations will be repeated in all five times, the connections on the control switch bank permitting the same number of impulses to be sent each time till the stepping of the control switch after the release of relay SZ following the fifth train of impulses extends earth from wiper 106, seventh bank contact, conductor 127, winding of relay SC to battery, and the operation of relay SC at 85 armature 82 disconnects earth impulses from the two-step relay PA and the sending switch magnet. The number which has thus been impaled to the coder is 44444, of which the first digit serves to effect the selection and connecting up of compensating resistances in the coder so that the retransmitted coded pulses may always be effective over substantially the same junction resistance, while the remaining four digits represent a wanted subscriber's number. The operation of the pause timing switch in the manner described ensures a definite pause between each train of impulses, thereby ensuring that the necessary switching operations take place in the coder before the next train of impulses is transmitted. The length of this pause may be altered if so desired by altering the connections on the banks of the pause timing switch. The number that has just been transmitted is stored in the coder and prepares circuits therein so that the number may be transmitted in the form of directional current impulses conveniently known as "light negative", "positive" and "heavy negative", as is fully described in the Passmore patent previously referred to. As soon as the coder is seized, battery and earth are connected to the line leads from the coder. These battery and earth connections are through the windings of retard TR and may be traced from the positive line from the coder, bank contact and wiper 131 of the secondary distributor SD, bank contact and wiper 132 of the primary distributor PD, conductor 133, working contact of armature 64, conductor 134, resting contacts of armatures 135 and 136, conductor 137, resting contact of armature 138, conductor 139, lower winding of retard TR to battery, and earth through the upper winding of retard TR, conductor 140, resting contact of armature 141, conductor 415, working contact of armature 62, conductor 142, wiper 143 and bank contact of the primary distributor PD, wiper 144 and bank contact of the 100 105 110 115 120 125 130

secondary distributor SD, to the other line to the coder.

Under the conditions of a normal call the coder will not send while there is battery and earth on the lines and waits for the removal of these connections by a switching operation at the distant end of the junction indicating that the equipment is prepared for the reception of coded pulses. In order to check that 10 the coder does not send prematurely the routining equipment is arranged so that a delay takes place before permitting the coder to send. It will be remembered that relay SDD operated as soon as relay B operated, and now 15 earth over wiper 106 and seventh bank contact of the control switch CS, conductor 127 and working contact of armature 145 operates relay SDR. Relay SDR upon operating extends earth pulses at conveniently the rate of 20 one pulse every four seconds from conductor 146 over working contact of armature 147, conductor 148, resting contact of armature 149, upper winding of two-step relay DLP to battery. Relay DLP closes its light armature 25 150 thereby preparing a locking circuit for itself which will become effective at the conclusion of the pulse. When this occurs relay DLP operates fully and is maintained from earth, working contact of armature 152, 30 conductor 151, working contact of armature 150, both windings in series to battery. An indicating lamp circuit is also closed from earth at armature 153, conductor 154, resting contact of armature 155, lamp to battery, to 35 indicate the state of the test. The next earth impulse received will operate relay DL over the working contact of armature 149, and resting contacts controlled by armature 156. Relay DL upon operating closes a locking 40 circuit for itself at armature 156 to conductor 127 and earth at the control switch wiper 106; at armature 155 opens the indicating lamp circuit; at armature 157 prepares the circuit for the relays LN, LP and HN and at armatures 138 and 141 disconnects the line leads 45 from the coder from battery and earth through retard TR and transfers them to the relays LN, LP and HN. This removal of current from the lines allows the coder to 50 start transmitting the number in the form of coded pulses, which will be received and recorded by the routining equipment. It will be noticed that a time interval takes place before retard TR is disconnected and the coder 55 is permitted to send, and this delay serves to check that the coder does not send prematurely. As soon as the coder commences to send it connects a guarding earth to the release trunk conductor, and if sending should take 60 place prematurely this earth will shunt relay PS which will then release, completing a circuit from earth, working contact of armature 73 of relay SS, Fig. 5, conductor 74, working contact of armature 75, conductor 76, resting 65 contacts of armatures 77 and 78, lamp 405,

upper winding of relay PSS to battery. Relay PSS energizes, thereby closing a circuit for the lower winding of relay FA at armature 80 and a locking circuit for itself at armature 29. Relay FA brings in the alarm 70 circuit, while the glowing of the lamp 405, which is maintained from the earth on the release key over conductor 230 and armatures 229 and 80, in series with the upper low resistance winding of relay PSS, indicates the 75 nature of the trouble. It will be seen, however, that as soon as relay DL operates to disconnect relay TR from the lines, a point is opened in the energizing circuit of relay PSS at armature 78, so that when the coder functions correctly, that is waits till battery and earth are removed from the lines before sending, the release of relay PS when the release trunk is earthed by the coder at that stage is 80 ineffective.

Assuming that the coder functions correctly, the coded pulses sent out will be received by relays LN, HN and LP, which are adapted to respond to currents in certain directions and of certain magnitudes only. Thus relay LN operates with a "light negative" pulse, and LP with a "light positive" pulse, that is, a pulse of similar strength but in the reverse direction, while a "heavy negative" pulse that is a pulse similar to a "light negative" pulse but of greater strength will 90 operate both relays LN and HN. A "light negative" pulse, however, is not of sufficient strength to operate relay HN which is marginally adjusted. The code corresponding to the digit 4 consists of a "light negative" pulse, a "light positive" pulse and a second "light negative" pulse, and this combination will be sent out four times to give the number 4444. The circuit of relays LN, LP and HN across the leads from the coder may be traced from bank contact and wiper 131 of the secondary distributor SD, bank contact and wiper 132 of the primary distributor PD, conductor 133, working contact of armature 64, conductor 134, resting contacts of armatures 135 and 136, conductor 137, working contact of armature 138, conductor 160, winding of relay IC, resting contact of armature 161, conductor 162, working contact of armature 157, conductor 163, windings of relays LP, HN and LN in series, resting contact of armature 164, conductor 165, working contact of armature 141, conductor 415, working contact of armature 62, conductor 142, wiper 143 and bank contact of the primary distributor PD, wiper 144 and bank contact of the secondary distributor SD and thence to the coder. The first pulse received from the coder, which will be a "light negative" pulse, will operate relay LN thereby extending earth from working contact of armature 20 of relay ST, conductor 48, resting contact of armature 47, conductor 167, working contact of armature 168, conductor 130

169, working contact of armature 170, conductor 171, resting contact of armature 172, upper winding of two-step relay QA, resistance 175 to battery, and also to the winding 5 of relay QS to battery by way of resting contact of armature 176. Relay QS operates and prepares a locking circuit for relay QA which will become effective when relay LN restores. As soon as relay LN restores, the 10 earth on conductor 169 is extended over working contact 174, both windings of relay QA in series, resistance 175 to battery, causing relay QA to operate fully. Relay QS is maintained at this stage by this earth through the 15 lower winding of relay QA, resting contact of armature 176, relay QS to battery. The next pulse received which is a "light positive" pulse, operates relay LP thus extending the previously traced earth on conductor 169 over 20 working contact of armature 177, conductor 178, working contact of armature 179, conductor 180, resting contact of armature 181, upper winding of storing relay MY to battery. Relay MY operates and at armature 25 182 closes a locking circuit for itself to conductor 183 and the earth on conductor 169 as previously traced. The next pulse received—a "light negative"—extends earth over armature 170, conductor 171, working 30 contact of armature 172, upper winding of two-step relay QZ, resistance 184 to battery. Relay QZ closes its light armature 185 and as its lower winding is then short-circuited it will remain in this condition till relay LN 35 restores. The earth that energized the upper winding of relay QZ is also extended to relay XM over conductor 183, resting contact of armature 187, winding of relay XM to battery, and relay XM closes contacts 188 to 40 prepare an operating circuit for switching relay MS which, however, cannot yet operate due to the fact that it is short-circuited. When relay LN restores after the pulse, the short-circuiting earth is removed and relay 45 MS operates in series with relay XM which also remains in the operated position, the holding circuit for these relays being from the earth on conductor 183 as previously traced. The release of relay LN also allows relay QZ 50 to operate completely and lock itself over both its windings in series, working contacts of armatures 185 and 174, conductor 169, to earth over the circuit already traced. The complete operation of relay QZ however 55 opens the holding circuit of relay QS at armature 176 and QS releases in turn thereby opening the holding circuit of relays QA and QZ at armature 174 so that these relays restore also. The three relays QS, QA and 60 QZ are now normal and ready for further impulses. The operation of relay MS, Fig. 1, transfers the leads from the first group of storing relays MW, MX, MY and MZ to the second group CW, CX, CY and CZ at armatures 187, 189, 181 and 190, and the second

digit to be received (which is also 4) will cause the operation of relays LN and LP, QS, QA and QZ in exactly similar manner to that just described, though this time relay CY of the second storing group will be operated and 70 relays XC and CS will be energized thereafter to effect the switching of the leads to the third group, which comprises relays DW, DX, DY and DZ and switching relays XD and DS. The third and fourth digits will 75 be received in similar manner causing the operation of storing relays DY and UY in the third and fourth storing groups respectively, the operation of relay DS switching the leads from the third to the fourth group, and relay US operating on the completion of 80 the coded pulses, that is, after the reception of the last digit.

When relay DL operated, it extended earth 85 pulses, conveniently every two seconds, from conductor 191, working contact of armature 192, conductor 193, resting contacts of armatures 194 and 195, lower winding of two-step relay Q to battery, and the first pulse received will cause relay Q to close its light 90 armature 196. At the termination of the pulse, relay Q will operate fully and will then be maintained from earth, working contact of armature 197, conductor 198, working contact of armature 196, upper winding of 95 relay Q, resting contact of armature 195, lower winding to battery. As soon as relay US operates after the storing of the fourth digit, earth is extended from resting contact of armature 208 of relay CD, Fig. 5, conductor 209, working contact of armature 210, conductor 211, winding of relay S to battery. Relay S operates and at armature 195 100 opens the circuit of relay Q allowing it to release, and at armature 246 extends the earth from armature 208, conductor 209 and conductor 200 to contacts of the storing relays and thence to indicating lamps. As the digit 4 was received by each group, and thus relays MY, CY, DY and UY respectively are operated, the earth on conductor 200 will be extended for instance in the third group, over resting contacts of armatures 201, 202 and 203, working contacts of armature 204, lamp 4, conductor 205, resting contact of armature 206, resistance 207 to battery, and also via similar circuits in the other groups to conductor 205 and battery. Therefore the number 4444 will be displayed on the panel situated adjacent to the routining equipment, 110 thus providing a visual indication that the correct number has been received.

The operation of relay S also connects earth impulses from conductor 191, working contact of armature 212, conductors 213, resting contact of armature 416 to two-step relay TS which operates in the well-known manner locking to earth on working contact of armature 214 over conductor 215 and armature 216, and extends the next pulse to two- 115 120 125 130

step relay TSR, which in turn extends the succeeding pulse to relay CD over resting contact of armature 217 and conductor 218. Relay CD operates in due course and locks itself at armature 219 to earth at armature 220 of slow relay SS; at armature 61 opens the circuit of relay SS, at armature 208 removes earth from relay S and the display lamps so that relay S restores and the lamps 5 are extinguished; at armature 286 completes a holding circuit for relay ET, the function of which is described later; at armature 66 removes earth from the indicating lamp lighted over wiper 68 of the test switch, and 10 at armature 221 extends earth over conductor 222 to energize the driving magnet DM5 of the test switch TS. When relay CD restores on the release of relay SS, the magnet DM5 will de-energize and move the wipers 15 to the second set of contacts and now, therefore, the second test indicating lamp will be lit. The releasing of relay S allowed relays TS and TSR to restore and the circuits are now prepared for the commencement of the 20 second test. Before the description of the next test is taken up it will be convenient to consider the results of incorrect sending by the coder. Several possibilities may arise, for example, no pulses at all may be received 25 by the storing relays, due perhaps to premature sending as mentioned earlier, or a number may be partially set, or it may be sent incorrectly and a wrong display result. 30 To take the first case, if no pulses are received, none of the group switching relays MS, CS, DS or US will be operated and therefore relay S will not operate to open the circuit of two-step relay Q. Consequently, the next pulse received over conductor 191 35 will operate relay QR over the working contact of armature 194 and resting contacts controlled by armature 244, and relay QR will lock itself at armature 244 to earth on key 231 over conductor 247. A circuit is now 40 completed from earth, resting contact of armature 223 of relay NC, Fig. 8, conductor 224, working contact of armature 225, conductor 226, resting contact of armature 227, lamp 228, conductor 235 to battery through 45 the low resistance upper winding of relay FA. Relay FA operates and at armature 229 locks itself over conductor 230, springs of key 231, resting contact of armature 233 to earth. At armature 234 an alarm lamp 332 50 is lit and an audible signal BL energized. The test cannot proceed any further and the signal will call the attention of the attendant, who must operate key 231 before relays QR and FA can be released. The glowing of the 55 "no pulses received" lamp 228 indicates the nature of the trouble. It will be appreciated that the period of the earth pulses on conductor 191 is such that ample time is allowed for the storing relays to be set up and relays 60 US and S operated when, in the normal case, 55

the coded pulses are completely received before the next pulse occurs to operate relay QR, and as the operation of relay S releases two-step relay Q there is thus no possibility of the alarm being falsely given. 70

In the case where all of the pulses are not received, the switching relay MS of the first storing group will be operated, but the switching relay US of the last storing group will still be normal. As before, therefore, relay Q will remain operated and relay QR will be energized in due course and relay FA will now be energized in series with lamp 236 and the working contact of armature 227, conductor 226, working contact of armature 225, conductor 224, resting contact of armature 223 to earth. Relay FA operates and locks itself to bring in the alarm as before, while the glowing of "number partially received" lamp 236 indicates the nature of the 75 trouble. 80

In the case of the number being incorrectly transmitted and a wrong number resulting on the display lamps, it will be seen that the battery feed to all display lamps in each set except the fourth is at this stage from conductor 237 and the winding of relay WN. As lamps 8 are used for further tests at a later stage, their battery circuit it will be noted extends from relay WN over conductor 238, 90 resting contact of armature 239, and conductor 240. If therefore any pulses are incorrectly transmitted, a circuit for a lamp other than 4 will be closed when relay S operates and consequently relay WN will be energized. Thereupon at armature 241 earth is extended from resting contact of armature 250 by way of "wrong number" lamp 243 and conductor 418 to the low resistance upper winding of relay FA and relay FA energizes 95 to bring in the alarm circuit as before. 100

A further operating feature of the coder circuit that is checked at this stage is the connecting of earth by the coder to the release trunk conductor as soon as it starts sending. This is to ensure that if the calling subscriber clears down while the coder is sending the coder is guarded until the sending switch has completed its operation and returned to normal. The earth placed on the guarding conductor by the coder at this stage shunts down relay PS, as previously described, but the release of this relay is now without effect as the operating circuit for relay PSS is open at armature 78 of relay DL. It will be seen that as soon as the coder has sent the first digit and relay MS operates to switch the leads to the second storing group, a circuit is closed from earth, working contact of armature 275, resting contact of armature 276, conductor 277, winding of relay Z to battery. Relay Z operates and at armature 278 closes a locking circuit for itself over resting contact of armature 279, conductor 133 to earth at armature 130. At armature 280 relay Z prepares 110 115 120 125 130

an alarm circuit, and at the working contact of armature 54 the release trunk conductor of the coder under test, which is connected to the bank of wiper 32 of the secondary distributor, is transferred to the lower winding 5 of relay ET. If the release trunk is not earthed at this time relay ET will not operate and as soon as relay CS operates after the reception of the second digit earth is extended 10 from armature 281, conductor 282, resting contact of armature 283, lamp 284, low resistance winding of relay FA to battery to bring in the alarm as usual, the lamp 284 indicating the nature of the fault. If, 15 however, the release trunk is correctly guarded, relay ET will operate, locking itself on its second winding at armature 285 to earth on conductor 169 and opening a point in the alarm circuit at armature 283.

20 At the conclusion of sending the code, the coder applies momentary earth to the pulse conductor in order to effect a switching operation at the repeater being used on the call. In the case of routine tests this earth on the 25 pulse conductor operates relay EP, over a circuit from the pulse conductor, bank contact and wiper 105 of the secondary distributor, bank contact and wiper 104 of the primary distributor, conductor 103, working 30 contact of armature 63, conductor 102, working contact of armature 101, conductor 287, winding of relay EP to battery. The operation of relay EP opens the locking circuit of relay Z and, as the initial energizing circuit 35 of relay Z is broken when relay CS operates, relay Z releases. The guarding conductor of the coder is now re-guarded through the low resistance winding of relay PS as before. If earth is not received on the pulse 40 lead after the code is sent, relay EP will not operate, consequently relay Z remains locked and as soon as relay TSR operates in the manner previously described, an alarm circuit is closed from earth, working contacts of armatures 288 and 280, lamp 289, low resistance 45 upper winding of relay FA to battery.

Returning now to consideration of the further progress of a successful test, the number 4444 will be displayed and after a short 50 pause this number will be extinguished and the test switch stepped to its second position in the manner already described. The circuit of relay SDD, Fig. 6, is therefore opened and that of relay DC completed, from earth, 55 wiper 50 of the test switch, second bank contact, normal springs of key 251, conductor 252, winding of relay DC to battery. Moreover, the release of relay CD again completes the circuit for relay SS at the back contact of 60 armature 61 and relay SS upon operating, at armature 130 connects earth to conductor 131, bank contact and wiper 132 of the control switch CS, interrupter springs and magnet DM4 to battery so that the control switch 65 wipers will be advanced to the ninth set of

contacts. The impulse springs 81 are now extended to the two-step relay PA at armature 83, and when relay PA has operated in known manner, pulses are transmitted to the 70 sender switch driving magnet DM3 and the sending switch wipers will therefore be stepped round the bank. The operation of relays SA, RA and RB now take place as already described and causes earth impulses 75 to be connected to the pulse conductor to the coder. When four such impulses have been sent, earth is extended over wiper 106 of the control switch, 9th bank contact, conductor 107, resting contact of armature 108, conductor 109, bank contact and wiper 110 of 80 the sending switch and conductor 111 to operate relay SZ. The sending switch will then be brought to a normal position; the pause timing switch will be operated to ensure the correct pause between digits and the control 85 switch will be advanced one step. The sending switch will then again rotate and earth pulses will be applied to the pulse conductor to the coder. It will now be noticed that due to the operation of relay DC, eight such 90 pulses will be sent to the coder before relay SZ is operated and the sending switch is brought to its normal position, the circuit to operate relay SZ being now from earth, wiper 106 of the control switch, 10th bank contact, conductor 125, working contact of armature 126, resting contact of armature 253, conductor 254 to bank 110 of the sending switch and thence to relay SZ, and for succeeding operations of the sending switch this circuit is 95 again completed over contacts 11, 12 and 13 of the control switch which are commoned together and to contact 10. The digits 100 impelled to the coder for this position of the test switch are therefore 48888, the digit 4 105 effecting the determination of the junction compensating resistance value and 8888 being equivalent to a subscriber's number. The control switch will now be on the 14th set of contacts and relay SC will operate, and as relay 110 SDD is normal relay DL will be operated immediately from earth, wiper 106 and 14th bank contact, conductor 127, resting contact of armature 255, conductor 256, winding of 115 relay DL to battery. As the delayed sending feature has already been tested on the first test, it is eliminated on succeeding tests by operating relay DL as soon as the control switch is stepped after the last digit is sent into the coder. The operation of relay DL 120 disconnects battery and earth through the winding of retard TR, from the line leads from the coder and thereupon the coder transmits the number in the form of coded pulses. Due to the operation of relay DC, 125 battery for display lamps 8 is now fed through resistance 207, working contact of armature 239 and conductor 240, while battery for lamps 4 is now through the winding of relay WN, conductor 238, the working contact 130

of armature 206 and conductor 205, so that if any lamp other than "8" be lit, the "wrong number" signal will be brought into operation. The operations of receiving the number in coded form, displaying it, and stepping the test switch to the third set of contacts, together with the arrangements for operating alarm circuits if the number is incorrectly or inadequately received, are identical with those already described and will be readily followed from the previous description. In this case however the digit 8 is being transmitted, the corresponding code being a "light positive" pulse, a "heavy negative" pulse and another "heavy negative" pulse. As previously pointed out, heavy negative pulses operate both relays HN and LN, and the relays which are operated in the first storing group to give the digit 8 are MW, MX and MZ, a similar combination being set up in other storing groups. Relay IC, Fig. 6, also responds to the heavy pulses, but its operation is ineffective at this stage. At the successful conclusion of the reception and display of the number 8888 the test switch is advanced to the third set of contacts, the third indicating lamp is lit from bank 68, and a circuit is completed for relay NC from earth, wiper 50 and third bank contact of the test switch, normal contacts of key 257, conductor 258, winding of relay NC to battery.

The function of the coder which it is now desired to check is the correct addition of resistance to the junction during the pulsing period to compensate for differences in length of the junctions to which the coder may be connected, so that the coded pulses may always be effective over substantially the same junction resistance. As is described in Patent No. 1,716,563, this compensation is effected by sending an additional digit into the coder previous to the subscriber's number, this digit being previously determined by the trunking scheme. This digit may conveniently be either 1, 2, 3 or 4, so that if the junction over which the call is to be completed is, for example, in the neighbourhood of maximum resistance, the extra digit 4 is sent and the coder circuit is arranged so that this digit brings no additional resistance into the pulsing circuit. Should the junction be of minimum resistance, the digit 1 will bring sufficient additional resistance into the pulsing circuit so that the junction may be of substantially the same total resistance as before, while digits 2 and 3 serve to effect intermediate adjustments for intermediate junction resistances. The operation of relay NC maintains relay DC at armature 260, and at armatures 164 and 161 connects the upper winding of relay LD across the line leads from the coder in place of the relays LN, LP and HN. The operation of sending a number into the coder now proceeds as before, the first, or compensating digit being 4 as

before, while due to the operation of relays NC and DC the subscriber's number is now 7777. The circuit to stop the sending after 7 pulses have been sent may be traced from earth, wiper 106 of the control switch, 17th bank contact on which it is now resting, conductor 125, working contacts of armatures 126 and 253 to sending switch bank 110 and thence to relay SZ and as the control switch steps after each digit, this circuit is the same for each sending operation due to the commoning between contacts 17, 18, 19 and 20 on bank 106. The number thus transmitted is 7777 preceded as usual by the compensating digit 4. Relays DL and SC operate as soon as the control switch is stepped to the 21st position and thereupon the coder will transmit the code pulses corresponding to the number 7777. The code for digit 7 consists of two heavy negative pulses and therefore eight such pulses in all should be received. The first pulse received will operate relays IC and LD and at armature 261 relay LD closes a locking circuit for itself over conductor 262 to earth at working contact of armature 197. Furthermore, at armatures 263 and 264 the coded pulses are transferred to the windings of differential relay CRF. It will now be seen that, due to the operation of relays NC and LD, the "decoding" relays LN, LP and HN are replaced by the differential relay CRF; accordingly the numbers received will not be displayed on the lamp panel, it being intended at this stage merely to check the correct operation of the coder circuit in inserting the appropriate value of junction compensating resistance in response to the initial digit dialled. The circuits over which the coded pulses are now received may be traced from the negative line from the coder, bank contact and wiper 131 of the secondary distributor SD, bank contact and wiper 132 of the primary distributor PD, conductor 133, working contact of armature 64, conductor 134, resting contacts of armatures 135 and 136, conductor 137, working contact of armature 138, conductor 160, winding of relay IC, working contact of armature 161, working contact of armature 264, lower winding of relay CRF to battery and also from the positive line from the coder, bank contact and wiper 144 of the secondary distributor SD, bank contact and wiper 143 of the primary distributor PD, conductor 142, working contact of armature 62, conductor 415, working contact of armature 141, conductor 165, working contact of armature 164, working contact of armature 263, upper winding of relay CRF to earth. The coded pulses from the coder corresponding to digit 7, that is the heavy negative pulses, consist of earth connected to the negative line, and battery, through such resistances as have been brought into circuit by the compensating digit, connected to the positive line. As

the compensating digit in this test was 4, no resistance should be included in the battery circuit, and also as relays CRB and CRA are normal there is no resistance in the other conductor. Relay CRF is differentially wound and if, therefore, the coder relays controlling the compensating resistance values have correctly responded to the initial digit, differential relay CRF will not operate with the pulses. Relay IC however operates and extends earth from working contact of armature 265, working contact of armature 266, conductor 267, driving magnet DM6 of the counting switch CGS to battery. As there are eight pulses in all, this circuit will be closed eight times and consequently the counting switch will be advanced eight steps so that the wipers are now on the ninth set of contacts. Earth will then be extended from wiper 268, 9th bank contact, conductor 269, winding of relay LI to battery so that relay LI operates. The operation of relay LI prepares a circuit at armature 271 to permit the operation of relay EP with the earth received from the coder on the pulse conductor as soon as the complete code has been sent, and as soon as relay EP has operated earth is extended from working contact of armature 290, conductor 291, working contact of armature 292, resting contact of armature 217, conductor 218, winding of relay CD to battery. The operation of relay CD energizes the driving magnet of the test switch and also effects the necessary circuit changes in a manner already described so that the next test can proceed. Moreover earth is extended from resting contact of armature 300, conductor 301, bank contacts and wiper 302 of the counting switch CGS and thence to the driving magnet DM6 by way of interrupter springs 303 to cause the wipers of the counting switch to be moved to the home position, thus breaking the circuit of relay LI which releases. The test switch wipers are now on the 4th set of contacts, the appropriate lamp is lit from bank 68 and earth is extended from wiper 50 over normal springs of the key 294, conductor 295, lower winding of relay CRA to battery. Relay CRA operates, thereupon at armature 296 maintaining relay NC energized; at armature 135 removing the short circuit from resistance 297, and at armature 108 extending earth from the control switch wiper 106, conductor 107, working contact of armature 108, resting contact of armature 298, conductor 299, to the third lead from the sender switch bank 110. The operations of sending a number into the coder will now proceed exactly as before described with the exception that due to the operation of relay CRA the initial digit sent to the coder to determine the compensating resistance value is 3; the remainder of the number is as before 7777. The compensating digit 3 serves

to bring into the coder impulse sending circuit a certain value of resistance in order to make the coded pulses effective over substantially a standard junction value while it will be noticed that the operation of relay CRA has introduced the resistance 297 into the circuit of the differential relay CRF. This resistance is so chosen that it balances the resistance that the coder should include in the impulsing circuit in response to digit 3, consequently when the coder sends out the eight "heavy negative" pulses corresponding to 7777, and the circuit is switched to the differential relay CRF, this relay again does not operate. The pulses received from the coder cause relay IC to operate 8 times and consequently the counting switch CGS advances 8 steps as before, and relay LI thereupon operates and prepares the circuit of relay EP which operates immediately on the conclusion of the sending operation. Thereupon relay CD operates and the succeeding operations take place in a manner which will be readily followed from the description already given.

The test switch is now advanced to the fifth set of contacts in readiness for the next test and in this position relay CRA is released and relay CRB operated from wiper 50 over normal springs of key 304 and conductor 305. The operation of relay CRB introduces resistance 306 into circuit at armature 136; at armature 307 maintains relay NC operated and at armature 308 extends earth from wiper 106 of the control switch, conductor 107, working contact of armature 308, resting contact of armature 309, conductor 310 to the second lead to the sender switch bank. The first digit impulsed into the coder, that is the compensating digit, will therefore be 2 in this case followed thereafter by 7777 as usual. The resistance 306 brought into circuit by operation of relay CRB is chosen to balance that which is brought into the impulse circuit of the coder by the digit 2 and consequently on the coder sending the coded pulses the differential relay CRF does not operate.

On the next test which is carried out in the 6th position of the test switch, both relays CRA and CRB are operated, thereby introducing both resistances 306 and 297 into circuit, while at the working contacts of armatures 108 and 298 earth is extended from the control switch wiper 106 to the first lead from the sender switch bank, so that the compensating digit is in this case 1, followed thereafter by 7777. As in the previous tests, the resistances 306 and 297 are of a value to balance that included in the coder pulsing circuit by the initial digit 1, and on the consequent sending of the coded pulses the differential relay CRF still does not operate. It follows therefore that during any of the preceding tests, if the relays in the coder cir-

cuit controlling the compensating resistance values correctly respond to the initial digit, the differential relay CRF does not operate. Should any case occur however in which the 5 resistance included in the impulsing circuit does not balance that introduced into the circuit of the differential relay CRF, this relay will operate and at armature 333 energize relay CFA over springs controlled by armature 334. Relay CFA upon operating, locks itself at armature 334 to earth on the release key 231 over conductor 335, and at armature 336 energizes relay FA by way of the "compensating failure" lamp 337 and conductor 10 418 and relay FA will thereupon bring in the alarm, the lamp 337 indicating the nature of the fault. Relays CFA and FA will restore when the release key is operated.

On the satisfactory conclusion of the tests 20 described, the test switch is advanced to the seventh set of contacts, thereby opening the circuit of relays CRA and CRB, and these relays release allowing relays NC and DC to restore. Furthermore over wiper 50 and the 25 seventh contact in its bank earth is extended over conductor 311 to operate relay TSH and also relay SDS and this circuit is maintained until the test switch reaches the home contacts. At armature 312 relay TSH extends 30 earth over conductor 313 to bank 314 of the test switch and thence over interrupter springs 315 to driving magnet DM5 of the test switch and the test switch wipers will therefore be advanced in known manner to 35 their normal position. Relay SDS at armature 47 opens the locking circuit of relay B which therefore releases and at armatures 62, 63, 64 and 56 disconnects the test leads to the primary distributor. Relay SDS 40 moreover at armature 316 extends earth from springs of step-on key 317, springs of reset key 318, resting contact of armature 319, working contact of armature 316, conductor 320, lower springs of continuous routine key 45 12, conductor 18, wiper 19 of the primary distributor to the driving magnet DM2 of the secondary distributor. The circuit of relay SDS is opened when the test switch reaches the home position and after its slow 50 releasing period it restores thereby opening the circuit to the driving magnet DM2 of the secondary distributor with the result that the wipers of the switch SD are moved to the next set of contacts. Thereupon the same 55 series of tests are carried out on the coder reached from that set of contacts and when these are completed, the switch again advances and in similar manner the tests are performed on the subsequent coders.

60 In this way all the coders available from this secondary distributor will be tested and when the secondary distributor steps after testing the last coder available from its bank earth will be extended from resting contact 65 of armature 69, conductor 70, wiper 71 and

bank contact of the primary distributor PD, wiper 72 and bank contact of the secondary distributor, conductor 321, upper winding of relay DH to battery. Relay DH is common to all secondary distributors and conductor 70 323 is commoned to the 25th contacts of banks such as 324 of all secondary distributors. Further, relay DH carries a sufficient number of armatures such as 325 and 325' to cover each secondary distributor equipped and consequently on the operation of relay DH the 75 secondary distributor is brought to the home position, the earth from armature 325 being extended over conductor 326 to bank 324. Moreover at armature 327 earth is connected 80 to conductor 13, driving magnet DM1 of the primary distributor PD to battery to energize the magnet. Relay DH releases as soon as the secondary distributor is in its normal position, thereby opening the circuit of the 85 driving magnet DM1 of the primary distributor PD and allowing it to restore. The wipers of the primary distributor will thus be moved forward one step and will then engage contacts associated with the second secondary distributor and tests will be carried out on all coders available from this secondary distributor.

When all the coders available from all the 90 secondary distributors have been tested in this manner, the primary distributor will be advanced to a point in its bank to which lamp 329 is connected, the lamp being wired to that contact immediately following the last secondary distributor. In this position a 95 circuit is closed from earth, resting contact of armature 69, conductor 70, wiper 71 and bank contact of the primary distributor, lamp 329, conductor 330, winding of relay FR to battery. Relay FR operates and at armature 100 331 actuates an audible signal, BL together with a visual signal 332 to call the attention of the attendant, while the glowing of the "test completed" lamp 329 indicates that all coders have been rouined. Restoration of 105 the start key 10 then allows the various distributors to return to normal.

Dealing now with the alarm circuits more in detail, it will be seen that in the event of a fault occurring the appropriate indicating 115 lamp is lit in series with one winding of either relay FA or FR. The lamps connected to the winding of relay FA may be designated as follows: "no earth on release trunk" (284), "no pulses received" (228), "number partially received" (236), "wrong number" (243), "no earth on pulse conductor" (289), "compensating relay failure" (337), while those connected to relay FR are: "test completed" 120 (329), "coder busy" (342), and "routine stopped" (343). The operation of relay FR energizes the audible signal BL and visual signal 332, while relay FA, providing a locking circuit for itself at armature 229, energ- 125 130

gizes the same alarm circuit. Relay FA also opens a point in the operating circuit of relay CD at armature 217 and at armature 344 closes a point in the circuit to lock the storing relays, so that in the event of the fault occurring in connection with the storing and display of a number, relay CD will not operate and also such storing relays as have been operated will be maintained so that it is possible to obtain some idea of the nature of the fault by noting what has been displayed on the panel. A further alarm circuit is provided by relay X which is in series with the test indicating lamps connected to bank 68 of the test switch, and which is arranged to bring in a delayed alarm. Under normal conditions the holding time of a coder, that is the total time taken in sending a number into the coder and subsequently receiving the coded pulses when the equipment is suitably prepared to receive them is comparatively short, but if during the testing operation this time should become excessive, as might occur for example if the coder failed to store the digits, the alarm circuit is brought into operation in the following manner. The operation of relay X in series with the test indicating lamps extends earth pulses, conveniently at the rate of one per minute, from conductor 345, front contact of armature 346, back contact of armature 347, lower winding of two-step relay TAR to battery. Relay TAR closes its light armature 348 thereby preparing a full locking circuit for itself which becomes effective at the termination of the pulse when the relay operates fully. If now for any reason the test is delayed excessively, the next time pulse will operate relay TA by way of the front contacts of armatures 346 and 347 and springs controlled by armature 350. Relay TA thereupon locks itself over armature 350 and conductor 351 to earth on the release key 231 and at armature 352 energizes relay FR in series with the "routine stopped" lamp 343, whereupon relay FR brings the alarm into operation. Each time the test switch steps after the satisfactory conclusion of each test, the circuit of relay X is opened at armature 66 by the operation of relay CD, and this prevents the time periods of each test becoming cumulative on the delayed alarm circuit, by allowing relay TAR to restore.

As pointed out above, at the commencement of the testing cycle on each coder, a test is first made to determine if the coder is busy. If it is busy the routining equipment waits, as on a regular call the coder should be returned to common use after only a short holding time. If the wait becomes excessive, as for instance would occur if a coder that had been artificially busied was encountered, the routining equipment passes on to the next coder but causes the indicating lamp associated with the coder found busy to flash.

A second coder found busy for an excessive time while the first is still unattended to will cause the routine to be stopped. Assuming now that a coder is found busy, relay A is maintained operated from the earth on the 76 coder guarding conductor, and extends time pulse conductor 353 by way of front contact of armature 41, back contact of armature 354, upper winding of two-step relay TP to battery. If relay A is maintained excessively 75 the time pulse earth on conductor 353, which may conveniently be each minute, will cause relay TP to close its light armature 355 thereby preparing a locking circuit for itself which will become effective as soon as the 80 time pulse earth terminates. The next time pulse received will operate relay SDS unless in the meantime the coder becomes available in which case relay A releases and allows relay B to operate, and also allows relay TP 85 to restore. Assuming however that the next time pulse is effective, relay SDS will operate from conductor 353, working contacts of armatures 41 and 354, conductor 357, resting contact of armature 358; conductor 359, winding of relay SDS to battery. Relay SDS locks itself at armature 360 to earth over conductor 361, armature 362, conductor 363 and armature 364. Relay TSH also operates in parallel with relay SDS over conductor 311 90 but as the test switch is already in normal position the operation of relay TSH is ineffective. At armature 45 relay SDS opens a point in the energizing circuit of relay B, and at armature 316 closes a circuit to energize the magnet of the secondary distributor from earth, springs of keys 317 and 318, resting contact of armature 319; working contact of armature 316, conductor 320, springs of key 12, conductor 18, wiper 19 and bank contact of the primary distributor, driving magnet DM2 of the secondary distributor to battery. Furthermore, earth from working contacts of armatures 365 and 366, conductor 367, resting contact of armatures 370 and 371 of all relays 100 such as FLA and FLB, to the bank 368 of the busy marking switch BS causes the energization of the driving magnet DM7 by way of the interrupter springs 369 so that the wipers of the busy marking switch will commence 105 to rotate in known manner. It must be understood that the busy marking switch carries one level such as 372 for each secondary distributor; an additional switch may be provided if one switch would need to be of 110 too great capacity. Associated with each bank 372 is a relay such as FLA and in the drawing two such banks 372 and 372' and associated relays FLA and FLB are shown. These banks 372, 372', . . . are multiplied to 115 the indicating lamp banks such as 72 of the corresponding secondary distributors and one of these lamps will already be lit from the resting contact of armature 69 over conductor 70 and wiper 71 of the primary dis- 120

tributor thus indicating the coder under test. This earth will be extended to the bank such as 372 of the busy marking switch and will cause the operation of the relay such as FLA 5 as soon as the busy marking switch wipers reach that contact. Assuming the coder is connected to the first secondary distributor, the earth will be extended over bank 372, resting contacts of armatures 373, 374 and similar armatures on similar relays, to the upper winding of relay FLA to battery. Relay FLA closes its contacts 375 which are adjusted to make first, thereby closing a locking circuit for itself to a release key 376. At armature 370 the driving earth is disconnected from the magnet DM7; at armature 377 relay FLR is operated in turn energizing relay CB in series with "1st coder busy" lamp 419 to bring in a non-urgent alarm circuit at 10 armature 420; and at armature 373 intermittent earth from conductor 378 is extended to bank 372 and thence to the indicating lamp which therefore flashes. The operation of relay FLR opens the locking circuit of relay SDS which releases, allowing the magnet DM2 of the secondary distributor to de-energize and move the wipers to the next contacts and thereafter the tests will proceed on this and subsequent coders. The non-urgent 15 alarm calls the attention of the attendant, the "1st coder busy" lamp 419 indicates the trouble and the flashing of the indicating lamp indicates which coder has been found busy. If a second coder is found busy before the first one is attended to and the release key 376 thrown to release relay FLA, relay A will be maintained energized as before and extend the time pulse earth firstly to operate the two-step relay TP and secondly over front contact 20 of armature 358 as relay FLR is still energized, conductor 379 to the winding of relay AL to battery. Relay AL operates, at armature 380 locking itself to earth at the release key 231; at armature 356 opening the holding circuit of relay TP; and at armature 381 energizing relay FR through the "coder busy" lamp 342. The operation of relay FR actuates the audible and visual alarm circuits as already described.

25 Various keys are included in the routining equipment to provide special facilities. These keys comprise the continuous routine key 12, the step-on key 317, the reset key 318, the busy test key 35, and the cancel test keys 51, 251, 257, 294, 304, 382. The continuous routine key is used when it is desired to continuously test one particular piece of apparatus. For this purpose a busying plug is inserted in the jack such as 391 associated with the appropriate coder indicating lamp and the continuous routine key 12, Fig. 6, is operated. Relay CR then operates, but owing to its slow to operate feature, a momentary earth is extended from the key 12 over back contact of armature 383, other springs of the key, conductor 30 313 to the driving magnet DM1 of the primary distributor causing it to take one step and thereby bring its wipers into connection with the first secondary distributor. At armature 384 of relay CR, earth is connected from resting contact of armature 15, conductor 16 to slow-to-operate relay CRR and also over the resting contact of armature 17 of relay CRR, conductor 18, wiper 19 and bank contact of the primary distributor to the magnet DM2 35 of the first secondary distributor with the result that this magnet is energized during the operating time of relay CRR. This circuit is broken when relay CRR is operated and the magnet releases moving the wipers forward one step so that they are now in contact with the first coder. At armature 69 of relay CR relay K is connected to wiper 72 of the secondary distributor; at armature 385 earth is removed from the homing bank of the primary distributor; and at armatures such as 28 and 30 the homing circuits of the secondary distributors are opened. Earth from resting contact of armature 24 is now connected over resting contact of armature 386, conductor 387, wiper 388 and bank contact of the primary distributor, bank 324 of the secondary distributor to the driving magnet DM2 over the interrupter springs 389. The secondary distributor wipers will therefore rotate and, assuming that the desired coder is connected to the second secondary distributor, the first distributor will rotate round the bank energising relay DH over its lower winding in series with the driving magnet when it reaches the 25th contact. Relay DH operates and at armature 390 extends full earth to operate the magnet and step the wipers off the 25th contact. At the same time relay DH extends earth from armature 327 and conductor 13 to energize the driving magnet DM1 of the primary distributor. Relay DH releases as soon as the secondary distributor steps off the last contact, and the circuit of the primary distributor magnet DM1 is thus broken and the wipers moved into connection with the second secondary distributor. This distributor thereupon rotates until it encounters the contact which is earthed by the insertion of the plug into a jack such as 391. This earth will be extended over wiper 72 of the secondary distributor, wiper 71 of the primary distributor, conductor 70, front contact of armature 69, winding of relay K to battery. Relay K at armature 386 disconnects the earth which is causing the rotation of the distributor switch, thus preventing the switch stepping further, and at armature 392 operates relay ST whereupon the test will thus be started in the usual manner. Owing to the fact that the stepping circuit for the secondary distributor at the conclusion of the test cycle is opened by the operation of the key, the tests will be repeatedly performed on the same coder. The method 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

of inserting a plug into the jack associated with required coder obviates the necessity of manually stepping the distributors by means of stepping keys.

5 The reset key 318 is used when it is desired to restart the test on a coder, for instance when a fault has been encountered. Momentary operation of the reset key 318 extends earth to slow-to-operate relay RES and over 10 resting contact of armature 393 of this relay to relay DSR which therefore receives a pulse during the operating time of relay RES. A similar pulse is given to relays SDS and TH over armature 394 of relay RES and 15 these relays operate, relay SDS providing a locking circuit for relay DSR at armature 395 via armature 396. The operation of relays SDS and TSH causes the test switch to return to the normal position and also opens 20 the circuit of relay B as previously described, while due to the operation of relay DSR the stepping circuit to step the secondary distributor magnet is opened at armature 19. As soon as the test switch is normal the holding 25 circuit for relay SDS and TSH is opened and these relays restore and relay B will then re-operate and the test will recommence on the same coder.

The step-on key 317 is used when it is desired 30 to pass from one coder to the next. Operation of key 317 extends earth to operate relay SO, and relay SO extends earth from armatures 397 and 398 to relays SDS, TSH, RES and DSR, the initial circuit of relays 35 SDS and DSR being opened as soon as relay RES is fully operated. These relays are held however as just described and a locking circuit is provided for relay SO at armatures 399 and 400. The test switch now returns to 40 its normal position and due to the operation of relay SO a stepping circuit is provided for the secondary distributor magnet at armature 401 by way of the working contacts of armatures 319 and 316. As soon as the test switch 45 reaches its normal position, relay SDS releases and allows DSR to restore, and in turn relays SO and RES. The secondary distributor magnet thereupon de-energizes and moves the wipers forward so that they are 50 now in contact with the next coder and the tests will now proceed on this coder.

The cancel test keys 51, 251, 257, 294, 204 and 382 are provided so that any of the six 55 tests may be cancelled if desired. Operation of any of these keys opens the lead from bank 50 of the test switch which normally prepares the testing circuits and connects earth from working contact of armature 410, conductor 42, key in operated position to bank 402 of the test switch. As soon therefore as 60 the test switch wipers are stepped to this contact at the conclusion of the previous section of the test, the magnet will be immediately 65 energized from bank 402 over the interrupter

springs 315, and the wipers will take another step and pass on to the succeeding test.

The busy test key is provided in order to check the operation of the routining equipment when it meets a piece of apparatus in 70 the engaged condition, so that the attendant can assure himself that the routining equipment will not cut in on engaged apparatus. Busy test key 35 is included in the circuit from the release trunk conductor of the coder 75 under test, between the primary distributor and the testing relays. Operation of the key extends earth to conductor 36, working contact of armature 21, conductor 37 and to the winding of relay A over the testing contact of 80 armature 56, or to conductor 55 and relay PS or ET over armature 54 of relay Z depending on the period of the test at which the key is operated. By this means the correct functioning of the routining equipment to a 85 guarded release trunk at various stages of the test can be checked.

It frequently occurs, particularly in large installations, that pieces of equipment may 90 be temporarily omitted, for instance certain shelves may be only partially equipped initially and be fully equipped at a later date. The routining equipment may conveniently be made to pass over such unequipped spaces 95 by connecting a strap (not shown in the drawings) between bank 324 and the appropriate contact of bank 72 of the secondary distributor. As soon therefore as the secondary distributor steps to such an unequipped space, earth from resting contact of armature 69, conductor 70, wiper 71 and bank contact of 100 the primary distributor, wiper 72 and bank contact of the secondary distributor, the strap (not shown in the drawings) between contacts of bank 72 and bank 324, interrupter 105 springs 389, driving magnet DM2 to battery and the driving magnet thereupon again energizes and moves the wipers to the next set of contacts.

What I claim as new and desire to secure by 110 Letters Patent is:—

1. In a telephone system employing apparatus having as one function the alteration of the resistance of control circuits, a routine test mechanism, a control circuit, means in 115 said mechanism for actuating said apparatus to perform alterations in the resistance of said control circuit, and means in said mechanism for performing complementary alterations therein to check the performance 120 of said apparatus.

2. In a telephone system employing a switching device having a control circuit including resistances, a test mechanism for said switching device, a control circuit in said mechanism including resistances, means in 125 said mechanism for actuating said switching device to perform alterations in the resistances of the control circuit thereof, and means in said mechanism to perform comple- 130

- mentary alterations in the resistances of the control circuit therein to compensate for the effect of the alterations in the control circuit of said switching device.
3. In a telephone system employing a switching device having a control circuit including resistances, a test mechanism for said switching device having a control circuit including resistances, means in said mechanism for actuating said switching device to perform alterations in the resistances of its control circuit, means in said mechanism to perform complementary alterations in the resistances of its control circuit, a differential relay, and means for executing said alterations over the windings of said differential relay to check whether corresponding alterations are performed in the resistances of said control circuits.
4. In a telephone system employing a switching device having a control circuit comprising resistances, a test mechanism for said switching device having a control circuit comprising resistances, means for actuating said switching device to perform alterations in the resistances of its control circuit, means in said mechanism to perform complementary alterations in its control circuit, a differential relay having two windings, means for including said relay in said control circuits and for executing said alterations over said windings, said relay being inoperative as long as said alterations correspond, signals, and means actuated by said relay if said alterations diverge for operating said signals to indicate the discrepancy in said control circuits.
5. In a telephone system employing a switching device having a control circuit comprising resistances, a routine test mechanism for said device also having a control circuit comprising resistances, means for actuating said switching device to perform alterations in the resistances of its control circuit, means in said mechanism to perform compensating alterations in its control circuit, a differential relay having two windings, means for including said relay in said control circuits and for executing said alterations over said windings, said relay being inoperative as long as said alterations correspond, means in said switching device to complete said control circuit intermittently, and a relay in series with said differential relay operable responsive to the completion of said control circuits regardless of the alterations therein.
6. In a telephone system employing a switching device having a control circuit comprising resistances, a test mechanism therefor also having a control circuit comprising resistances, means for actuating said switching device and said mechanism to perform corresponding changes in the resistances of said control circuits, a differential relay having two windings connected in series with another relay, means for including the windings of said differential relay in said control circuits and for executing said changes thereover, said differential relay being inoperative if said changes correspond, means for completing said control circuit intermittently, said other relay being operable responsive to said completions of said control circuit regardless of the changes therein, a stepping device, and means operated by said relay to actuate said stepping device.
7. In a telephone system employing a switching device having a control circuit comprising resistances, a test mechanism therefor also having a control circuit comprising resistances, means for transmitting impulses to said switching device for actuating the same to transmit corresponding impulses to said test mechanism and to perform thereby alterations in the resistances of its control circuit, means in said mechanism to perform corresponding alterations in its control circuit, a differential relay having two windings, circuit means for including said windings in said control circuits, said relay being inoperative if said alterations correspond, means for closing said control circuits intermittently, another relay operative responsive to said closures regardless of the correspondence between said control circuits, a stepping device, means operated by said other relay for actuating said stepping device, and means actuated by said stepping device for performing circuit changes in response to the receipt of the appropriate number of impulses transmitted from said switching device.
8. In a telephone system employing a plurality of switching devices, a routine test mechanism therefor including switching means for progressively connecting said mechanism with said devices, means in said mechanism for subjecting a device connected with to a series of functional tests, means in said mechanism for delaying the application of said tests for a predetermined period of time when the device connected with is busy, and means automatically operable for actuating said switching means at the expiration of said period to connect said mechanism with the succeeding switching device.
9. In a telephone system employing a plurality of pieces of apparatus, testing equipment, means for automatically associating said equipment with said pieces one after another, means responsive to the association of said equipment with a busy piece of apparatus for operating said first means after a predetermined interval of time to associate said equipment with another piece, and means responsive to said operation for hunting for said busy piece.
10. In a telephone system employing a

plurality of pieces of apparatus, testing equipment for routine testing said pieces, step-by-step distributor switches, means for operating said switches to associate said equipment with said pieces one after another, means responsive to the association of said equipment with a busy piece for operating said distributor switches after a certain time period to associate said equipment with another piece of apparatus, an auxiliary step-by-step switch, and means responsive to the operation of said distributor switches after said time period for operating said auxiliary switch to hunt for said busy piece of apparatus.

11. In a telephone system employing a plurality of switching devices, a routine test mechanism therefor having switching means for progressively connecting said mechanism with said devices, means in said mechanism for subjecting an idle device connected with to a series of functional tests, means for delaying the application of said tests for a predetermined period of time when the device connected with is busy, means for actuating said switching means at the expiration of said period to connect said mechanism with the succeeding device, a special switch, means for actuating said special switch to connect with said busy device, signals, and means operated by said special switch to actuate said signals to indicate said busy device.

12. In a telephone system employing a plurality of switching devices, a routine test mechanism therefor including switching means for progressively connecting said mechanism with said devices, means in said mechanism for automatically subjecting a device connected with to a series of functional tests, special marking means provided for each of said devices, and means responsive to the operation of any one of said marking means for automatically actuating said switching means to connect said mechanism with the switching device corresponding thereto to repeatedly apply to it said series of functional tests.

13. In a telephone system employing a plurality of switching devices, a routine test mechanism therefor including switching means for automatically and progressively connecting said mechanism with said devices in a certain order, means in said mechanism for automatically subjecting a device connected with to a series of functional tests, discriminating means, means responsive to the operation thereof for automatically actuating said switching means to connect said test mechanism with a certain one of said devices, and means for subjecting said device continuously and repeatedly to said series of functional tests.

14. In a telephone system employing a plurality of switching devices, a routine test mechanism therefor including switching

means for automatically and progressively connecting said mechanism with said devices, means in said mechanism for subjecting a device connected with to a series of functional tests, means in said mechanism for delaying the application of said tests for a predetermined period of time when the device connected with is busy, means for actuating said switching means at the expiration of said period to connect said mechanism with the succeeding device, and means for preventing further operation of said switching means if said succeeding device remains busy longer than said time period.

15. In a telephone system employing a plurality of switching devices, a routine test mechanism therefor having switching means for progressively connecting said mechanism with said devices, means for subjecting an idle device connected with to a series of functional tests, means for delaying the application of said tests for a predetermined period of time in case the device connected with is busy, means for actuating said switching means to connect said mechanism with the succeeding device, a special switch, means for actuating said switch to connect with said busy device, signals, means operated by said switch to actuate said signals to indicate said busy device, other signals, and means for stopping the progress of the test and for actuating said other signals if said succeeding device connected with is busy.

16. In a telephone system employing apparatus for receiving and reproducing impulses, a test mechanism therefor, means in said mechanism for transmitting to said apparatus successive trains of impulses, a pause timing switch for controlling the pause between said successive trains of impulses, and means in said mechanism for receiving and checking the impulses reproduced by said apparatus.

17. In a telephone system employing apparatus for receiving impulses of a certain character and reproducing them as impulses of a different character, a test mechanism therefor, means in said mechanism for transmitting to said apparatus successive trains of impulses of a certain character, a stepping switch for controlling the pause between said successive trains of impulses, and means in said mechanism for receiving and checking the different character impulses transmitted by said apparatus.

18. In a telephone system employing switches for receiving impulses of one character and call value and retransmitting them as impulses of another character and the same call value, a testing mechanism for said switches, means in said mechanism for transmitting to a switch successive trains of impulses of a certain character and a definite call value, a stepping device for controlling the pause between said successive trains of impulses.

impulses, and means in said mechanism for receiving and checking the impulses of a different character but corresponding call value transmitted by said switch.

- 5 19. In a telephone system employing a plurality of switching devices, a routine test mechanism therefor including means for automatically and progressively connecting said mechanism with said devices, means in said mechanism for automatically subjecting a device connected with to a series of different functional tests, and means for automatically causing said mechanism to skip any one of said tests.
- 10 20. In a telephone system employing a plurality of switching devices, a routine test mechanism therefor including means for automatically and progressively connecting said mechanism with said devices, means in said mechanism for automatically subjecting a device connected with to a series of different functional tests in a definite order, a key in said mechanism for each of said tests, and means responsive to the operation of any one 25 of said keys for causing said mechanism to skip the test represented by the operated key.

21. In a telephone system employing a plurality of switching devices, a routine test mechanism therefor including means for automatically and progressively connecting said mechanism with said devices, means in said mechanism responsive to the connection thereof with one of said devices for automatically applying to that device a series of functional tests in a definite order, means for arresting the operation of said mechanism if the device under test fails to respond properly to any one of said tests, and means for thereafter resetting said mechanism to commence the reapplication of said tests to the 40 device under test.

22. In a telephone system employing a plurality of switching devices, a routine test mechanism therefor including means for automatically and progressively connecting said mechanism with said devices, said mechanism having a normal position, means in said mechanism responsive to the connection thereof with one of said devices for operating said mechanism from its normal position to apply a series of functional tests to that device in a definite order, means for arresting the operation of said mechanism when the device under test fails to respond properly to one of 55 said tests, a key, and means responsive to the operation of said key after the arresting of said mechanism for restoring said mechanism to its normal position to commence the reapplication of the tests to the device under test.

- 60 23. In a telephone system employing a plurality of switching devices, a routine testing mechanism therefor including means for automatically and progressively connecting said mechanism to said devices, means in said mechanism for automatically subjecting the

device connected with to a series of functional tests, means responsive to the connection of said mechanism with a busy device for preventing said mechanism subjecting that device to said tests, and means in said mechanism for simulating the connection of said mechanism to a busy device to check the operation of said preventing means.

In testimony whereof I have signed my name at Liverpool, England, this 30 day of March, 1928.

LANCELOT MARTIN SIMPSON.
